DESIGN FOR A COMBINATION FRAME

Robert O. Kirchhan, Milwaukee, Wis., assignor to Milwaukee Brass Specialty Company, Milwaukee,
Wis., a partnership composed of Charles
O. Kirchhan and Robert O. Kirchhan

Application March 31, 1939, Serial No. 83,953

Term of patent 14 years

To all whom it may concern:

Be it known that I, Robert O. Kirchhan, a citizen of the United States, residing at Milwaukee, in the county of Milwaukee and State of Wisconsin, have invented a new, original, and ornamental Design for a Combination Frame, of which the following is a specification, reference being had to the accompanying drawing, forming part thereof.

I claim:

The ornamental design for a combination frame, as shown.

ROBERT O. KIRCHHAN.
